DESIGN FOR A PENCIL SHARPENER

Åke Jarl Erik Kihlberg, Stockholm, Sweden, assignor to Instrumentaktiebolaget J. A. Palm, Stockholm, Sweden

Application December 31, 1946, Serial No. 135,856
In Sweden December 19, 1946

Term of patent 14 years

(Cl. D74—23)

To all whom it may concern:

Be it known that I, Åke Jarl Erik Kihlberg, a subject of the King of Sweden, residing at Stockholm, Sweden, have invented a new, original, and ornamental Design for Pencil Sharpener, of which the following is a specification, reference being had to the accompanying drawing, forming part thereof.

Fig. 1 is a side perspective view of a pencil sharpener;

Fig. 2 is a side elevation slightly in perspective and with the head drawn outwardly; and

Fig. 3 is an end elevation viewed from the left of Fig. 2, showing my new design.

I claim:

The ornamental design for a pencil sharpener, as shown.

ÅKE JARL ERIK KIHLBERG.
